Primary Examiner — Brett Miller(74) *Attorney, Agent, or Firm* — Notaro, Michalos & Zaccaria P.C.(57) **CLAIM**

The ornamental design for an electric hamburger grill, as shown and described.

DESCRIPTION

FIG. 1 is a perspective view of an electric hamburger grill showing my design therefor;

FIG. 2 is a front elevational view thereof;

FIG. 3 is a rear elevational view thereof;

FIG. 4 is a side elevational view;

FIG. 5 is a top plan view thereof; and,

FIG. 6 is a bottom plan view thereof.

The broken lines depict portions of the grill that form no part of the claimed design.
